DESIGN FOR A GAS SAVER

Guy F. Goddeau, Chicago, Ill., assignor to The
Liquid Carbonic Corporation, Chicago, Ill., a
corporation of Delaware

Application August 6, 1945, Serial No. 121,252

Term of patent 7 years

(Cl. D54—13)

To all whom it may concern:

Be it known that I, Guy F. Goddeau, a citizen
of the United States, residing at Chicago, in the
county of Cook and State of Illinois, have in-
vented a new, original, and ornamental Design
for Gas Saver, of which the following is a speci-
fication, reference being had to the accompany-
ing drawing forming a part thereof.

Fig. 1 is a top plan view of a gas saver embody-
ing my new design;

Fig. 2 is a side elevation thereof;

Fig. 3 is an end elevation, taken from the left
of Fig. 1; and

Fig. 4 is an end elevation, taken from the right
of Fig. 1.

I claim:

The ornamental design for a gas saver, as
shown.

GUY F. GODDEAU.
